TRITIUM LABELING PROCESS

August Y. Mottlau, Rahway, N.J., assignor to Esso Research and Engineering Company, a corporation of Delaware
No Drawing. Filed Nov. 12, 1959, Ser. No. 852,223
1 Claim. (Cl. 260—675)

The present invention relates to an improved technique for labeling or tagging hydrocarbons with tritium in order to aid in the control of processes and reactions, particularly those processes and reactions involved in refining petroleum and petroleum products. Tritium labeling is called tritiation.

A technique of labeling hydrocarbons by placing them in intimate contact with curie amounts of tritium gas has been accomplished in the past by Riesz and Wilzbach, *Journal of Physical Chemistry*, 62, 6 (1958) and Wilzbach, *J. Am. Chem. Soc.* 79, 1013 (1957). In most cases, the tritiated product desired is the original parent compound changed only by having hydrogen atoms replaced by tritium atoms. However, a considerable amount of cracking or splitting of the hydrocarbon atoms occurs and several types of products of decomposition are produced. It is of course desirable that the tritiated parent constitute as high a proportion of the tritiated product as possible. In the petroleum industry where tracer compounds are extensively employed, it is generally desirable to employ liquid hydrocarbons in the labeling process and, for this reason, attempts have been made to minimize production of side products, particularly those which are normally gaseous, in labeling normally liquid hydrocarbons with tritium.

By the process of the present invention it has now been found possible to improve the degree of tritiation of a hydrocarbon while minimizing its breakdown. For example, normal hexane upon tritiation produces a tritiated C₆ fraction of about 40% greater yield than has heretofore been attained. At the same time, the degree of tritiation of that C₆ fraction has been increased as well. For example, the amount of tritiated C₆ fraction expressed in millicuries can be increased by about 77%.

In the present improvement, hydrocarbon either normally liquid or gaseous is tritiated in the presence of the noble gas, argon, employed in an amount up to a partial pressure approximately equal to the partial pressure of the tritium present for the purpose of improving the yield of the tritiated hydrocarbon product while minimizing the production of by-products. Using gaseous hexane, about 50% of the tritium introduced into hydrocarbon is found in products more volatile than hexane. However, when using liquid hexane for the reaction, the utilization of tritium by fixation into desirable liquid hydrocarbon is nearly doubled, i.e., from 25% to 48%. It is probable that the active volatile molecular fragments formed in the vapor phase by the prior technique react with tritium, which of course is plentifully present in that phase, with greater frequency than with other hydrocarbon fragments or molecules. On the other hand, although the present invention is not to be limited by a theory of its mechanism, in the liquid phase operation the opportunity for the triflating of those volatile fragments is less.

The use of argon evens out the tritium radiation energy so that this energy is transferred to the normally liquid hydrocarbon at more moderate levels, and as a result there is a marked reduction in the formation of cracked or other extraneous products of the reaction. Ideally, the tritium should be transferred 100% to the normally liquid hydrocarbon without the formation of any by-products except hydrogen. The present invention, while

2

not achieving the theoretically perfect transference of tritium, does improve upon the yields which were obtained by Riesz and Wilzbach, *supra*.

It is unnecessary to limit the hydrocarbon to be tritiated to one which is normally liquid. It is however desirable in practicing the instant novel process to carry out the reaction with at least a portion of the hydrocarbon being tritiated in the liquid phase. In other words, the use of superatmospheric pressure and reduced temperatures, if necessary, may be employed in order to maintain some liquid phase hydrocarbon for the tritiation reaction. Hydrocarbon in both liquid and vapor phase simultaneously, in liquid phase alone and in vapor or gas phase alone can be subjected to the novel tritiation reaction.

A series of experiments was undertaken employing normal hexane as the liquid hydrocarbon. The reaction was carried out at room temperature, and the closed containers were shaken for a period of two weeks while at room temperature.

Table I

Sample No.	n-Hexane ¹ (ml.-liquid)	Tritium (mm. Hg)	Argon (mm. Hg)
1	1	150	0
2	1	150	150
3	1	150	300

¹ n-Hexane has a vapor pressure at room temperature of about 150 mm. Hg, which is the same as the partial pressure of the tritium.

At the end of the reaction period, the hexane and the radiolysis products were frozen with liquid nitrogen and the fixed gases were pumped off. To minimize evaporation loss, samples were chilled with Dry Ice. Tritium distribution, as a C₆ fraction, a lighter than C₆ fraction, and a heavier than C₆ fraction was determined for each of the three samples shown above using a radioassaying gas chromatograph. This instrument is similar to that used by Riesz and Wilzbach, *supra*. The following results were obtained:

Table II

Sample No.	Argon mm. Hg	Tritium Distribution (Percent)		
		C ₆ —	C ₆	C ₇ thru C ₁₀
1	0	39	18	43
2	150	27	25	48
3	300	29	25	46

These data indicate that dilution with argon increases the amount of tritium incorporated into the C₆ fraction by almost 40% over the amount of tritium in the C₆ fraction when employing no argon. By doubling the partial pressure of argon over that shown in sample 2, no further improvement in the tritiation selectivity was found. The tritium employed and as used in the containers had a radioactive energy level of about 3 curies. The effect of the argon on the distribution of the tritiated products is apparent by studying the total millicuries of labeled hydrocarbons formed in each fraction. These values are obtained by multiplying a specific activity of each sample by the tritium distributions as shown in Table II. From the following table, it appears that a 1:1 argon-tritium dilution has little effect on the C₆ and lower compounds formed since only a slight reduction is indicated. The C₆ and heavier compounds however are markedly increased. A further dilution with argon to 2:1, as shown in sample 3, causes a pronounced and proportional decrease in the tritiation in each fraction.

3
Table III

Sample No.	Argon, mm.Hg	Specific Activity, mc./ml.	Millieuries by Fractions		
			C ₅ —	C ₆	C ₇ —C ₁₀
1.....	0	71	28	13	31
2.....	150	92	25	23	44
3.....	300	53	15	13	24

Argon, up to a volume equaling that of the tritium, serves to render more efficient and more uniform the distribution of the beta particles from the tritium. Part of the beta particle energy would be absorbed by the argon with the formation of ions (15.68 ev.) and meta-stable atoms (11.6 ev.) which, in turn, readily excite and ionize normal hexane (10.43 ev.). The net result is that there is a larger number of hydrocarbon molecules excited, but there is less destructive violence involved and any "overdose" of argon as for example in sample 3, merely acts as an inert diluent assisting in the thermal dissipation of the energy.

While the above samples were all carried out using normal hexane, it is to be understood that any normally liquid hydrocarbon or mixture of hydrocarbons can be similarly employed and additionally, as stated heretofore, liquefied normally gaseous hydrocarbons may be similarly treated although their usefulness as tracer compounds in refinery operations is more hazardous to health and also from the standpoint of ease of handling is less advantageous than the use of the normally liquid tritiated hydrocarbons. The tracer techniques employed in refin-

4

ery and chemical operations lend themselves more readily to the injection and tracing of normally liquid hydrocarbons, and these are preferred over the use of normally gaseous hydrocarbons.

5 The relative partial pressures as between the tritium and argon employed are generally about of equal degree. However, a lesser partial pressure may be employed and as sample number 3 illustrates, in some instances it is desirable to employ a greater partial pressure of argon than of the tritium, if the production of certain heavier fractions of hydrocarbons is desired.

Having now thus fully described and illustrated the character of the invention, what is desired to be secured by the Letters Patent is:

15 A process of tritiation which comprises contacting a normally liquid hydrocarbon a portion of which is in the liquid phase with tritium admixed with argon for a sufficient length of time to effect tritiation of said hydrocarbon, the partial pressure of tritium employed at least substantially equaling the vapor pressure of said hydrocarbon measured at atmospheric temperature and the partial pressure of argon employed substantially equaling that of the tritium.
